UNITED STATES PATENT OFFICE

114,353

DESIGN FOR A FILM VIEWING MACHINE

Harry E. Turner, Pacific Palisades, Calif., assignor
or of one-half to Arthur O. Garrett, Los Angeles, Calif.

Application February 6, 1939, Serial No. 82,803

Term of patent 7 years

To all whom it may concern:

Be it known that I, Harry E. Turner, a citizen of the United States, residing at Pacific Palisades, in the county of Los Angeles and State of California, have invented a new, original, and ornamental Design for a Film Viewing Machine, of which the following is a specification, reference being had to the accompanying drawing, forming a part thereof.

Figure 1 is a side elevational view of a film viewing machine showing my new design;

Figure 2 is a plan view thereof; and

Figure 3 is a front elevational view thereof.

I claim:

The ornamental design for a film viewing machine, as shown.

HARRY E. TURNER.
